UNITED STATES PATENT OFFICE.

CIRIACO TUASON, OF MANILA, PHILIPPINE ISLANDS.

COOK STOVE.

Application filed November 10, 1927. Serial No. 232,377.

My invention relates to cook stoves and has among its objects, to provide a cook stove which is particularly adapted to burn wood as a fuel; one wherein the heat is prevented from communicating to the exterior sides of the structure thus adapting the stove to be used in hot climates without subjecting the attendant to additional discomfort from heat, the construction being such that the major portion of the structure may be of wood; to provide a stove having associated therewith compartments in which the food can be kept warm after having been cooked, means being provided for the heating of hot water in a household supply tank; and generally to furnish a stove which is relatively simple and inexpensive in construction, convenient and economical in practical use, and which will be relatively light in weight so that it can be moved from place to place without difficulty.

The foregoing and other objects are attained by means of a novel combination and arrangement of parts to be hereinafter described and claimed, and in order that the same may be better understood reference should be had to the accompanying drawings forming a part of this specification.

In the drawings, wherein the same reference characters designate the same parts in all views,

Figure 1 is a front elevation of a stove constructed in accordance with my invention;

Figure 2 is a top plan view;

Figure 3 is a section on the line 3—3 of Figure 2;

Figure 4 is an end elevation;

Figure 5 is a cross section on the line 5—5 of Figure 2, and

Figure 6 is a cross section on the line 6—6 of Figure 2.

The drawings illustrate what now appears to be a preferred embodiment of the invention, but it is to be understood that the invention is capable of other mechanical expression without departing from the spirit and scope of the subject matter claimed hereinafter.

Referring to the drawings by reference characters, the stove comprises a rectangular frame constructed mainly of wood,—preferably Philippine hard wood. Of course the frame can be made of metal or any other material desired. The frame includes upstanding corner and intermediate posts 1, 1^a respectively, suitably connected by longi-

tudinal bars 2 and cross bars 3. This frame serves as a support for the stove proper which may be a more or less unitary metal structure comprising a fire-box 4 at one end,—a subjacent ash pit 5 separated from the fire-box by a grate 6; and a heat, flame and smoke passage 7 leading from the fire-box 4 toward the chimney 8 at the opposite end of the stove at which is also located the oven 9.

The refractory clay bottom of the ash pit 4 is supported by a galvanized iron plate 10 which, as shown in Figures 3 and 5, is supported by the longitudinal and cross frame members 2, 3 at one end of the frame. The ash pit is approximately one-third the length of the frame and, as shown in Figure 5, is about one-third the width of the frame being disposed centrally thereof. The space at either side of the ash pit 4 is filled with fire brick 11, refractory clay or the like. The grate 5 is supported upon the fire brick 11, as shown in Figure 5.

The fire compartment 4 is dimensioned similarly to the ash pit 5 and the sides thereof are separated from the outer walls of the stove proper by fire brick or refractory clay 11, as shown.

The cold water pipe 12 (preferably rose copper) is shown (Figures 1 and 5) leading from the household hot water tank 13 into the fire-box 4 and thence back to the hot water tank 13. Thus the stove supplies hot water for household use in addition to being available for cooking purposes.

In the end view, Figure 4, is shown the fuel door 4^a and the ash door 5^a.

Figure 3 shows a sheet iron partition 14 forming the inner end wall of the ash pit 95 and extending a substantial distance above the grate 6. This partition 14, of course, is coextensive with the width of the galvanized iron sheet 10 defining the bottom of the ash pit. Joining the upper end of the partition 14 is a sheet iron plate 15 of the same width as partition 14 and extending in the direction of the opposite end of the frame. Figure 3 also shows the horizontal plate 15 as being offset at 15^a at which point it is supported by a cross member 3 of the frame. Plate 15 supports the oven 9 in spaced relationship to the galvanized iron-lined walls 16 of a chamber 17 located at the end of the frame opposite to the fire-box 4. The oven 9 might be said to be suspended from the plate 15, which latter is formed with a mul-

105

110

tiplicity of slots or openings 15^b surrounding the oven 9, and between the walls thereof and the walls 16 of the chamber 17, so that the hot air coming from the fire-box can circulate around the side walls of the oven and the walls 16 of the chamber 17.

The top of the stove comprehends a cast iron plate 18 covering the entire area and provided, as shown in Figure 2, with a plurality of circular holes 19, which receive closure plates 19^a nested the one within the other, as shown. The closure plates 19^a are in alined series and are located immediately above the heat passage leading from the fire-box to the oven,—that is to say one hole 19 is immediately above the fire-box, one intermediate the ends of the heat passage 7 and the other immediately above the oven 9. The heat passage 7 is enlarged beneath holes 19 and constricted intermediate holes 19, as indicated at 7^a, to a width slightly less than the width of the fire-box 4, the sides of the heat passage being lined with fire brick or refractory clay 11, as shown. The bottom of the heat pasageway 7 is also lined with fire brick 11. The interior walls of the stove,—that is to say the side walls of the fire-box 4, heat passage 7 and the walls surrounding the compartment 17 are all lined 30 with asbestos 50 so as to keep the heat from radiating outwardly and to confine the heat within the relatively small area desired. Also the use of insulating material, (fire brick and asbestos) serves to effect an economy of fuel, in addition to avoiding the subjection of the attendant to discomfort from heat. The dotted lines in Figure 2 clearly show the confined area leading from the fire-box to the oven or rather to chamber 40 17,—through which the heat passes.

A chimney 8 is shown connected to a cast iron elbow 8^a which extends through the back wall of the chamber 17 (Figure 6).

Figure 1 shows the oven door 9^a and also 45 a register door 17^a which communicates with the chamber 17 which surrounds the oven. This register door can be open when it is desired to cool the oven or when it is desired to let some hot air out into the room, or 50 for cleaning purposes.

The side and end walls of the frame and also of the stove proper may be constructed of wood. I have shown the back of the 55 stove as being covered with a sheet of galvanized iron 25 which is coextensive in length and height with the entire unit.

The top plate 18 of the stove proper is shown as being provided with an extension at either side of the stove extending along 60 each longitudinal edge. This extension is in the form of a shelf 26 having an upstanding flange 26^a at its outer edge whereby the tile 27 can be laid upon the shelf and confined between the flange 26^a and the outer 65 longitudinal edge of the plate 18. The shelf

26 is supported by means of brackets 28 these being shown in Figure 4. While shelf 26 is shown on but the two sides a similar shelf may be provided at each end without requiring the exercise of invention.

70 Of course, the plate 10, forming the bottom of the ash pit, and the plate 15, together with the upstanding metal partition 14 may all be formed from one sheet of metal bent to shape. A suitable valve or damper 60 is provided which can be adjusted for diverting the products of combustion away from a direct path to the chimney forcing same to follow a tortuous course around the oven 9.

75 The area 30 inclosed by the frame of the device beneath the ash pit 5, heat passage 7 and chamber 17 may be utilized for keeping warm food which has already been cooked. As already mentioned this area is 80 inclosed. Where fire brick is used upon the bottoms of the ash pit, heat passage 7 or chamber 17, the courses of such fire brick or refractory clay 11 are made thin enough so that enough heat will pass in a downward direction to keep the subjacent space good and warm. Also holes may be cut in the bottom asbestos lining 50 of passage 7. Accordingly I provide glazed doors 29 at the front of the device and opening into 85 the area 30 beneath the stove proper. Of course the bottom of the food warming area, referred to, will be closed in by wood and also asbestos lining may be availed of so as to retain the heat.

90 100 By employing cleats 33 upon the posts 1, 1^a food supporting trays 34 can be positioned within the food warming compartment or area 30.

105 From the foregoing description read in connection with the accompanying drawings the various features of advantage, together with the details of construction of my stove are believed to be readily apparent to those skilled in the art. Inasmuch as the fire-box and associated passageways and chambers are separated from the sides of the stove and insulated therefrom the unit may be made substantially of wood and is available for manufacture in places where metal 110 is scarce. The ordinary difficulty with a stove for burning wood is that it takes a tremendous quantity of wood in order to produce sufficient heat to cook with. This is due to the fact that the heat is disbursed 115 over a wide area. In my stove the heat is confined to a relatively small area at the center of the stove which area is, however, ample for cooking purposes.

120 Having thus described my invention what I claim as new and desire to secure by Letters Patent is:

125 1. A cook stove comprising a wooden frame, a superstructure mounted upon said frame and having a fire compartment at 130

one end an oven compartment at the other end and a heat passage to establish communication between said fire compartment and said oven compartment, said superstructure having top, side, and bottom walls, the top wall of said heat passage having an opening, a heat plate adapted to close said opening, the side walls of said superstructure being relatively thick and of insulating material to thereby materially restrict the width of said fire-box and passage whereby the top and bottom walls will be subjected to a more intensified heat by reason of the limited area of said fire-box and passage, said passage being relatively enlarged beneath said heat plate, said frame being inclosed and having upstanding posts, trays supported by said posts for supporting food, and doors carried by said post whereby access may be had to the inclosed portion of said frame.

2. A cook stove comprising a frame, a superstructure mounted upon said frame and having a fire box, an oven chamber, an

oven in said chamber, a passageway connecting said fire box and oven chamber and located beneath the stove top, said passageway having an intermediate lineal area transversely widened to provide a heat pocket, webs for supporting said oven in said oven chamber, said webs being carried by the oven chamber wall and having openings therein to permit the free passage of gases about the oven, the top of said oven lying in a plane with the bottom of said passageway, a flue at one side of said oven chamber and spaced from the oven, a damper hinged below said flue opening and carried by the wall in which said flue opening is located, said damper extending between and engaging the end walls of the oven chamber and having its outer end adapted to engage the top wall of said oven, whereby the hot gases from said passage may be diverted at will for passage about said oven.

In testimony whereof I affix my signature.

CIRIACO TUASON.
